UNITED STATES PATENT OFFICE

2,338,903

FLUID OPERATED PUMP ASSEMBLY

Clarence J. Coberly, Los Angeles, Calif., assignor
to Roko Corporation, Reno, Nev., a corporation
of Nevada

Application January 21, 1941, Serial No. 375,219

18 Claims. (Cl. 103—46)

My invention relates to pumps of the character used for pumping oil from deep wells and relates in particular to pumps which are operated by fluid under pressure which is forced downwardly through suitable piping to a fluid motor unit forming part of the pump.

Although the invention is of especial utility with fluid operated pumps, it may be in many instances profitably employed with other types of pumps. Fluid operated deep well pumps are now used where it is desired to avoid sucker rods and the attendant losses and inefficiency. A type of fluid operated pump now in use employs an outer tube which is adapted to receive oil from the well and an inner tube having a pump connected to the lower end thereof and extended down into the well to such position that the intake of the pump will receive oil from the well. The pump is operated by clean operating fluid, such as oil, which is pumped downwardly through the inner tube to the pump unit. A pump of this character has been known to operate for a long period of time, but regardless of the high efficiency of the pump, such pump is subject to wear of its operating parts and must be removed as occasion demands. The known construction of such pumps, that is, with the pump secured to the lower end of the inner tube, requires the removal of the entire inner tube from the well in order to bring the pump to the surface. This requires considerable time and labor. For example, to pull a pump from a six thousand foot well requires a crew of four or five men and approximately four hours of time, and, in addition to this, the use of heavy equipment and considerable power.

It is an object of the present invention to provide a pumping equipment in which the pump constitutes a separate unit adapted to be lowered to the lower end of a tube in a well and to be removed from such tube by the action of an upward flow of fluid through the tube. With the invention in use, instead of four or five hours being required for pulling the pump, it may be pumped from the well in approximately one-half hour, the result being that a worn pump may be removed from a well and replaced by another in a period of one and one-half hours or less. The invention avoids the necessity of assembling a crew of men when it becomes necessary to pull the pump and also avoids the transporting of pulling equipment.

It is an object of the invention to provide a pumping equipment including means for pumping a clean operating fluid under high pressure

and relatively low velocity to a pump unit in a well for the purpose of operating such pump unit, and having improved means for reversing the flow of fluid and conducting the same at lower pressure and relatively high velocity in a manner to remove the pump unit from the well by the action of such reversed flow of fluid.

It is a further object of the invention to provide an improved means at the upper end of the well for receiving and holding the pump after it has been raised by fluid, such receiver being detachable from the upper end of the well structure so that the pump may be readily removed therefrom after the fluid has been turned off.

To accomplish the foregoing objects I have previously employed a pair of concentric tubings disposed in a well, the pump being received in the inner tubing and the production therefrom being conveyed to the surface of the ground through the outer tubing, as illustrated in my Patent No. 2,230,830, issued February 4, 1941, to which reference is hereby made. Such an installation requires an outer production tubing of relatively large diameter, which is quite expensive, the expense thereof making the cost of such an installation prohibitive in the case of a well having a low production capacity, with the result that the recognized benefits of such an installation system have not been commercially available for use in such small production capacity wells. It is therefore an object of my present invention to provide a two-tubing well system in which the production tubing may be of relatively small diameter to permit the use of the system in low production capacity wells, and I prefer to accomplish this by providing a pump tubing and a production tubing which are set side-by-side in the well.

A further object of my invention is to provide a well pump adapted to be pumped out of a well tubing by fluid pressure applied to the lower end thereof in which check valve means are provided in the pump for preventing a reverse flow of fluid through the pump as it is pumped out of the well tubing.

Another object of the invention is to provide a fluid operated well pump adapted to seat on a seat member in the well and constructed and arranged so that the discharge from the pump is adjacent the seat so as to prevent sand or other foreign material from collecting between the seat and the pump.

Still another object of the invention is to provide a novel type of valve mechanism adapted for use in a well pump, in which a valve member is

provided which is normally held off its seat to prevent wear thereon but which automatically engages said seat upon a reverse in flow of fluid through the valve mechanism. I prefer to accomplish this by providing magnetic means for normally holding the valve member off its seat.

Other objects and advantages of my invention will appear from the following specification and the drawings, which are for the purpose of illustration only and in which:

Fig. 1 is a vertical assembly view, partially in section, showing my invention installed in a well.

Fig. 2 is an enlarged cross-sectional view taken on the line 2—2 of Fig. 1.

Fig. 3 is an enlarged cross-sectional view taken on the line 3—3 of Fig. 1.

Fig. 4 is an enlarged vertical sectional view of the upper end of the device shown in Fig. 1.

Fig. 5 is a cross-sectional view taken on the line 5—5 of Fig. 4.

Fig. 6 is a cross-sectional view taken on the line 6—6 of Fig. 4.

Fig. 7 is an enlarged vertical sectional view of my pump unit, taken in the neighborhood of the line 2—2 of Fig. 1.

Fig. 8 is a vertical sectional view of my pump unit, being a downward extension of Fig. 7.

Fig. 9 is a vertical sectional view of my pump unit, being a downward extension of Fig. 8.

Fig. 10 is a vertical sectional view of my pump unit, being a downward extension of Fig. 9.

Fig. 11 is a cross-sectional view taken on the line 11—11 of Fig. 10.

Fig. 12 is a fragmentary elevational view of the tubular element 132 of my device.

Fig. 13 is a fragmentary sectional view of a portion of Fig. 10, with one of the parts removed.

Referring to the drawings, Fig. 1 shows a well casing 15 set in an oil well, as is well known in the art, so that the lower end thereof is open to an oil producing zone of the well, the upper end of the casing being provided with a casing head 16. Suitably suspended from the casing head 16 in any manner well known in the art is a pump tubing 17 having a lower collar 18 thereon, the lower end of the pump tubing being connected through a connecting collar 19 with a lower tubing 20 to the lower end of which is connected a foot member 21. As will be noted, the pump tubing 17 and the connecting collar 19 have the same internal diameter. Pumping means comprised of a fluid operated pump unit 23 is received in the lower tubing 20, and when in working position occupies the position shown in Fig. 1. Also suitably suspended from the casing head 16 is an auxiliary tubing 24 which extends through the casing head and is connected at its lower end to the foot member 21, its axis being parallel to but offset from the axis of the pump tubing 17. Enclosing the lower end of the pump tubing 17 and the lower end of the auxiliary tubing 24, and the foot member 21, is a gas anchor device 25.

Connected to the upper end of the pump tubing 17 and the auxiliary tubing 24 is a valve means 26 having a pump catcher 27 connected thereto in alignment with the pump tubing 17, and having a discharge pipe 28 and a supply pipe 29 connected thereto, the supply pipe being connected to a suitable high pressure pumping mechanism 30, and the discharge pipe being connected to a suitable point of discharge or storage (not shown).

Referring to Figs. 4, 5, and 6, the valve means

26 includes a valve block 32 having an upper threaded major bore 33 and a lower threaded major bore 34 axially aligned with each other and communicating through a central chamber 35. Threadedly received in the lower major bore 34 is the upper end of the pump tubing 17, and threaded into the upper major bore 33 is the lower end of a tubular member 36 of the pump catcher 27. Also provided in the valve block 32 is a tapered valve seat opening 37 connected with the central chamber 35 by means of a slot 38, the valve seat opening also being connected through a diametrically opposed slot 39 with an auxiliary bore 40 which communicates with the upper end of the auxiliary tubing 24 which is suitably connected to the valve block 32. Seated in the tapered valve seat opening 37 is a tapered valve member 42 having a first passage 43 and a second passage 44 therein, the passages preferably being of arcuate form as shown in Fig. 6. Formed on the upper end of the valve member 42 is a hollow stem 45, the upper end of the stem being threaded to receive a threaded plug bolt 46, there being a radial passage 47 communicating between the lower end of the interior of the hollow stem 45 and the periphery of the valve member 42, the radial passage being provided with an outwardly opening ball member 48. A lubricant, such as grease, may be provided in the interior of the hollow stem 45 so that by screwing the plug bolt 46 inwardly into the hollow stem the lubricant may be forced radially outwardly through the radial passage 47 onto the periphery of the valve member 42 to lubricate the same. Provided in the upper face of the valve block 32 is a counterbore 49 axially aligned with the valve seat opening 37, into which projects a plug 50 formed on a closure plate 51 which is suitably rigidly secured to the valve block 32, as by bolts 52, the closure plate being separated from the valve body by a gasket 53 forming a fluid-tight joint therebetween. The closure plate 51 is provided with a bore 55 of larger diameter than the external diameter of the hollow stem 45 so as to provide a space therebetween in which packing 56 is provided around the hollow stem, the packing being held between a packing gland member 57 threaded into the bore as at 58, or otherwise secured relative to the closure plate, and a packing ring 59 resting on ball bearings 60 provided between the lower face of the packing ring and the upper face of the tapered valve member 42. It will be apparent that by tightening the packing gland member 57 relative to the closure plate 51, the packing 56 may be compressed so as to prevent leakage of fluid past the hollow stem 45. The ball bearings 60 provide anti-friction means between the packing ring 59 and the tapered valve member 42 when the latter is rotated. The upper end 61 of the hollow stem 45 is preferably provided with square faces so as to receive a wrench by which the hollow stem and the attached tapered valve member 42 may be rotated.

Also provided in the valve block 32 is a discharge opening 62 and an inlet opening 63, these openings being so positioned relative to the slots 38 and 39 that when the tapered valve member 42 is in the position shown in Fig. 6, the first passage 43 therein will connect the slot 38 and the inlet opening 63, and the second passage 44 therein will connect the slot 39 and the discharge opening 62. By rotating the tapered valve member 42 ninety degrees in either direction, the slot 38 may be connected to the discharge open-

ing 62 and the slot 39 may be connected to the inlet opening 63. It will thus be appreciated that the valve means 26 provides a four-way valve. The supply pipe 29 is connected to the valve block 32 so as to communicate with the inlet opening 63, and the discharge pipe 28 is connected to the valve block 32 so as to communicate with the discharge opening 62, as shown in Fig. 6.

Also formed in the valve block 32 is a bleeder valve bore 155, the lower end of which communicates with the central chamber 35 through a port 156, the upper end of the valve bore being counterbored to provide a bleeder valve seat 157 on which seats a bleeder valve element 158 which is threaded into the valve bore and which is provided with a stuffing box 159 therearound to prevent fluid leakage past the bleeder valve element. The valve bore 155 above the valve seat 157 communicates through a bleeder port 170 with a bleeder pipe 171 which preferably extends downwardly through the casing head 16 into the well casing 15, although it may be connected to any desired point of discharge.

The pump catcher 27 includes a tubular body member 65, the lower end of which is threaded onto the upper end of the tubular member 36, there being a sealing ring 66 welded or otherwise secured to the member 36 so as to insure a fluid-tight joint between the tubular body member 65 and the tubular member 36. Provided in the tubular body member 65 are a pair of diametrically opposed openings 67 and 68 in which are received tubular elements 69 and 70, respectively, each of the tubular elements being provided with an end plug 71 threaded into the outer end thereof. The tubular element 69 is provided with a sliding dog 72 normally urged toward the interior of the tubular body member 65 by a coil spring 73, and the tubular element 70 is likewise provided with a sliding dog 74 normally urged toward the center of the tubular body member 65 by a coil spring 75. Each of the dogs 72 and 74 is undercut at its inner lower edge, as at 76, and the dogs form a latch means adapted to permit a tapered head member 77 to be passed therethrough but to retain the same after the head member rises above the dogs. A dash-pot element 78 is provided in the upper end of the tubular body member 65 and has a conical opening 79 therein adapted to receive the tapered head 77, the dash-pot element engaging each of the dogs 72 and 74 to limit the inward movement thereof, and being yieldably retained in such position by a coil spring 80. The clearance between the dash-pot element 78 and the inner wall of the tubular body member 65 is small, so that upward movement of the dash-pot element 78 is cushioned by fluid trapped thereabove, and it will be appreciated that this construction comprises a dash-pot means for cushioning final upward movement of the fluid operated pump unit 23.

As shown in Fig. 1, the head element 77 is fixed to the upper end of a perforated tubular strainer 81, the lower end of which is threadedly secured to a check valve device 82, which is shown in detail in Fig. 7. The check valve device 82 includes a body member 83, the upper end of which is threadedly secured to the lower end of the perforated tubular strainer 81, and the lower end of which is bored to provide a valve chamber 84, the lower portion of which is internally threaded, which communicates

through a bore 85 with the lower end of the strainer 81. Threaded into the valve chamber 84 is the upper end of a tubular element 86 provided with a main bore 87 and a valve bore 88

- 5 at the upper end thereof, the valve bore 88 being counterbored at its upper end to provide an upwardly faced check valve seat 89 on which a ball valve element 90 is adapted to seat to close the valve bore 88. A plurality of vertical passages 91 are provided in the upper end of the tubular element 86 and intersect the main bore 87 thereof below the check valve seat 89, and it is to be noted that such passages are of substantially smaller diameter than the valve bore 88, for a purpose to be described hereinafter. As will be noted, the outer surface of the tubular element 86 is relieved at 86a so that the lower end of the tubular element is of slightly greater diameter than the balance thereof.
- 10 The lower end of the tubular element 86 also forms part of a sealing member 92 and has a lower inwardly curved face 94 at its lower end and being threaded to a tubular element 95 having a flange 96, the upper face of which is inwardly curved as at 97 so as to hold an annular packing element 98 preferably formed of resilient material, such as synthetic rubber, between the curved face 94 and the flange 96. The tubular element 95 is provided with an annular
- 15 recess 93 which registers with the major portion of the inner surface of the annular packing element 98. Radial openings 99 are provided in the tubular element 95 so as to communicate with the recess 93 for a purpose to be described hereinafter. The lower end of the tubular element 95 is threaded to the upper end 100 of the fluid operated pump unit 23, and it is to be noted that the external diameter of the sealing member 92 is substantially the same as
- 20 the external diameter of the fluid operated pump unit, and that the sealing member makes a close sliding fit within the connecting collar 19, which is connected to the lower end of the pump tubing 17, although the upper portion of
- 25 the tubular element 86 above the relieved portion 86a has ample clearance in the tubing 17.
- 30
- 35
- 40
- 45

The fluid operated pump unit 23 may be of any desired type, although I prefer to use a fluid operated pump of the type shown and described in my copending application Serial No. 350,010, filed August 2, 1940, to which reference is hereby made for a complete description of the construction and operation of the specific fluid operated pump mechanism shown in the present application. Consequently, only the general elements of the fluid operated pump unit 23 will be described herein.

9. Disposed in the liner 109 is a piston 112 making a fluid-tight sliding fit with the interior of the liner and having a longitudinal bore 113 therethrough. Fixed to and carried by the piston 112 is a plug element 114 having an opening 115 therethrough communicating between the bore 113 and the discharge passage 105 at all times through the upper end of the liner 109 and a passage 116 formed in an intermediate member 117. Rigidly connected to the upper end of the plug element 114 is a pilot rod 118 which extends upwardly through the main valve member 103 and the tubular valve body 102, the upper end thereof projecting into the connecting pipe 86, as shown in Fig. 7. Fixed to the lower side of the piston 112 is a tubular element 119 having a working valve 120 secured in the lower end thereof, the tubular element projecting into a sleeve construction 121 in which the tubular element 119 makes a fluid-tight sliding fit.

Fixed to the lower end of the pump cylinder 108 is a lower cylinder 123, the upper end of which abuts against the lower end of the liner 109, and the lower end of which is threaded to a tubular seating member 124, as best shown in Fig. 10. An upwardly opening standing valve 125 is provided so as to close a central passage 126 through the seating member 124, the central passage communicating through the standing valve with the interior of the lower end of the sleeve construction 121, as best shown in Figs. 10 and 11. As will be noted, the lower end of the seating member 124 is provided with a conical face 127 adapted to seat in a conical opening 128 formed in the upper end of a lower check valve 35 means 129.

The lower check valve means 129 makes a close fluid-tight fit in a bore 131 provided in the foot member 21, and includes an upper tubular element 132 and a lower tubular element 133 threaded thereto. The upper tubular element 132 has a tubular member 134 disposed rigidly therein, or formed integrally therewith, the lower end being counterbored to receive a U-shaped permanent magnet 135 rigidly fixed therein, the permanent magnet being adapted to normally retain thereon by magnetism a metallic closure ball 137. The upper tubular element 132 is provided with a plurality of flow passages 160, radially spaced, only one of which is shown in Fig. 10, and is provided with a longitudinal slot 161 in one side thereof. The longitudinal slot, as shown in Fig. 12, is formed with an upper major portion 162 and a lower minor portion 163, the portions thereof being separated by shoulders 164 which are arcuate in form, as shown in Fig. 13. Received in the slot 161 is a release member 165 having shoulders 166 formed thereon which are adapted to seat on the shoulders 164 formed by the slot 161, the shoulders 166 having a lower arcuate face adapted to fit into the shoulders 164 of the slot. The release member 165 has an upper end 167 which, when the closure ball 137 is seated as shown in Fig. 10, projects into the line of the central passage 126, and has a lower curved end 168 which engages the closure ball 137. The release member 165 is also provided with a flat spring 169 secured thereto, which normally urges the upper end 167 of the release member into the line of the central passage 126.

The lower tubular element 133 is provided with a seating ring 138 on which the closure ball 137 may seat to close a central passage 139 formed in the lower tubular element 133. The lower end of the lower tubular element 133 is provided with

5 a conical seating face 140 adapted to seat in a conical opening 141 formed in a tubular inlet plug 142 threadedly secured in the lower end of the bore 131. As will be noted, the upper tubular element 132 is counterbored so as to provide an annular shoulder 143 for a purpose to be described hereinafter.

10 Also, as shown in Fig. 10, the foot member 21 is provided with an auxiliary bore 144 into which the lower end of the auxiliary tubing 24 is threaded, the lower end thereof communicating through a passage 145 with a chamber 146 formed in the upper end of the foot member 21 and intersecting and axially aligned with the bore 131. The chamber 146 also communicates with the lower end of the annular space 107.

15 The gas anchor device 25, shown in Fig. 1, is of conventional construction well known in the art and may be dispensed with if desired. The gas anchor device 25 includes a head member 148 through which the pump tubing 17 and the auxiliary tubing 24 extend, the head member abutting against the lower end of the lower collar 18. Abutting against the lower end of the head member 148 is a gas anchor barrel 149, the upper end of which is provided with perforations 150, and the lower end of which abuts against a tail member 151 secured to the foot member 21 by means of a bolt 152 threaded into a threaded opening 153 provided in the foot member. By tightening the bolt 152, the gas anchor barrel 149 may be rigidly clamped between the head member 148 and the tail member 151.

20 In operating my invention, the device is first installed in a well with the parts in the operating position shown in Fig. 1. During normal operation the four-way valve means 26 has the tapered valve member 42 in the position shown in Fig. 6. The high pressure pumping mechanism 30, which may be of any standard type of high pressure fluid pump well known in the art, is operated to convey an operating fluid, such as clean oil, through the supply pipe 29, the inlet opening 63, the first passage 43, the slot 38, the central chamber 35, and into the top of the pump tubing 17. The operating fluid passes downwardly through the pump tubing 17 and enters the perforated tubular strainer 81, passing downwardly therethrough and into the check valve device 82. Since the ball valve element 90 is normally in its seated position on the seat 89, the operating fluid flows downwardly therearound, through the vertical passages 91 into the tubular element 86, flowing therethrough and flowing through the sealing member 92 into the upper end 100 of the fluid operated pump unit 23. Operating fluid also flows outwardly through the radial openings 99 of the sealing member 92 into the annular recess 93 so as to force the annular packing element outwardly into sealing engagement with the interior of the connecting collar 19.

25 The fluid operated pump unit 23, as shown in Figs. 8 and 9, has its piston 112 in its uppermost position in the liner 109, the same having just completed its upstroke. In this position, the main valve member 103 is in its lowermost position in which the under face of the piston 112 is in fluid communication with the fluid discharge pressure in the annular space 107 through the radial opening 111, the longitudinal space 110, the longitudinal passage 104, and the discharge port 122. In this position of the main 30 valve member 103, the lower end thereof is open

to the discharge pressure in the discharge passage 105 through suitable grooves formed in the pilot rod 118 and suitable ports provided therefor. As will be noted, the upper end of the piston 112 is also in direct communication with the discharge pressure in the annular space 107 through the passage 116, the discharge passage 105, and the discharge port 106. Consequently, in this position of the parts, the fluid pressure is balanced on the upper and lower faces of the piston 112. The pressure of the operating fluid used to operate the fluid operated pump unit 23, as will be evident to those skilled in the art, is substantially higher than the fluid discharge pressure in the annular space 107, and since the pilot rod 118 extends upwardly into the tubular element 86, the operating fluid pressure at all times bears on the upper end of the pilot rod, and with the parts in the position shown in Figs. 8 and 9, in which the fluid pressures on the upper and lower faces of the piston 112 are balanced, the pressure of the operating fluid on the upper end of the pilot rod 118 causes the same to move downwardly, carrying with it the piston 112. This causes the downstroke of the piston 112, which also moves downwardly the tubular element 119 which is rigidly connected thereto. On the downstroke of the tubular element 119, since well fluid is trapped between the working valve 120 and the standing valve 125, the working valve 120 opens to permit well fluid therebelow to be displaced upwardly into the tubular element 119. When the piston 112 and the pilot rod 118 reach the end of their downstroke, high pressure operating fluid is admitted to the lower end of the main valve member 103 through suitable grooves cut in the top of the pilot rod, and since the main valve member is a differential-area valve it moves upwardly to an upper position in which operating fluid in the upper end of the tubular valve body 102 is admitted directly into the longitudinal passage 104 through an inlet port 122a formed in the main valve member 103. Operating fluid then flows downwardly through the longitudinal passage 104, the longitudinal space 110, and the radial opening 111 into the lower end of the liner 109 to bear against the lower face of the piston 112, causing the same to move upwardly to perform its upstroke. During the upstroke of the piston 112, the working valve 120 is closed, and the piston causes fluid thereabove in the liner 109 to discharge through the discharge passage 116, the discharge passage 105, and the discharge port 106 into the annular space 107. This pumped fluid from the well passes downwardly through the annular space 107 into the chamber 146 at the lower end of the fluid operated pump unit 23 and flows therefrom through the passage 145 and the auxiliary bore 144 formed in the foot member 21 into the lower end of the auxiliary tubing 24, through which it flows upwardly. From the upper end of the auxiliary tubing 24, the pumped well fluid flows into the auxiliary bore 40 formed in the valve block 32, passes therefrom through the slot 39 and the second passage 44 into the discharge opening 62, from which it discharges into the discharge pipe 28. Upon the upstroke of the traveling valve 120, suction is created therebeneath, causing the working valve 120 to open and permitting well fluid to flow upwardly therethrough.

Well fluid flows into the fluid operated pump unit 23 by first entering the gas anchor device 25 through the perforations 150 of the gas anchor

barrel 149, flowing downwardly in the gas anchor and entering the lower end of the tubular inlet plug 142, from which it flows upwardly through the central passage 139 in the lower tubular element 133, through the upper tubular element 132, through the central passage 126 of the tubular seating member 124, from which it passes through the standing valve 125. Consequently, it will be appreciated that the fluid operated pump unit 23 shown and described herein pumps on the upstroke of its piston 112, the discharge from the pump passing upwardly through the auxiliary tubing 24 to a suitable point of discharge. It will be appreciated, however, that any suitable type of pumping mechanism may be used in the well instead of the fluid operated pump unit 23 without departing from the spirit of the invention, and I do not intend to be limited to a fluid operated pump unit. It will also be appreciated that as soon as the fluid pressure above the metallic closure ball 137 is reduced below the pressure of the well fluid in the central passage 139, the closure ball 137 will be raised by this pressure differential so as to engage the permanent magnet 135, which thereafter holds the closure ball in open position during operation of the fluid operated pump unit 23, which is the normal position of the closure ball.

When it is desired to remove the fluid operated pump unit 23 from the well, for repairs or for any other reason, the tapered valve member 42 of the four-way valve means 26 is rotated ninety degrees in either direction, preferably by applying a suitable wrench to the upper end 61 of the hollow stem 45 thereof, which operation connects the inlet opening 63 with the auxiliary bore 40 of the valve block 32 through either of the passages 43 or 44, and which connects the discharge opening 62 and the central chamber 35 of the valve block through the other of the passages 43 or 44. By this adjustment, it will be appreciated that the auxiliary tubing 24 is connected to the supply pipe 29 and the pump tubing 17 is connected to the discharge pipe 28. Operating fluid then passes downwardly through the auxiliary tubing 24 and through the auxiliary bore 144 and passage 145 of the foot member 21 into the chamber 146 formed in the foot member. The pressure of the operating fluid is thus applied to the tubular seating member 124 attached to the lower end of the fluid operated pump unit 23, and this causes the fluid operated pump unit 23 to move upwardly through the lower tubing 20, the connecting collar 19, and the pump tubing 17. As soon as the tubular seating member 124 moves upwardly off its seat in the conical opening 128, operating fluid immediately tends to flow downwardly through the lower check valve means 129 and back into the well casing 16. However, downward movement of operating fluid past the metallic closure ball 137 of the lower check valve means 129 forces the same away from the permanent magnet 135 and causes it to seat on the seating ring 138, thus preventing further fluid flow downwardly through the central passage 139 of the lower tubular element 133. Thereafter, the weight of the column of fluid in the pump tubing above the metallic closure ball 137 causes the same to remain seated on the seating ring 138. It will be noted that the maximum external diameter of the tubular seating member 124 is considerably greater than the maximum external diameter of the seal formed between the conical

face 127 of the seating member and the conical opening 128 in the lower check valve means 129, which provides a difference in area against which the operating fluid admitted to the chamber 146 from the auxiliary tubing 24 can work to raise the seating member from its seat in the conical opening 128.

As indicated, the connecting collar 18 and the pump tubing 17 have approximately the same internal diameter, and since the annular packing element 98 of the sealing member 92 is expanded, a sliding fluid-tight fit is provided between the fluid operated pump unit 23 and the walls of the tubing through which it passes. Due to the relief at 86a on the tubular element 86, the latter does not tend to bind in the pump tubing as the unit is raised therethrough. As soon as the pressure in the pump tubing 17 above the fluid operated pump unit 23 is reduced, by adjustment of the four-way valve device 26, the ball valve element 88 of the check valve device 32 is no longer held on its seat 89 by fluid pressure thereabove, and since the cross-sectional area of the valve bore 88 is greater than the total of the cross-sectional areas of the vertical passages 91, the reverse flow of operating fluid passes through the valve bore to raise the ball valve element into the position shown in dotted lines in Fig. 7 in which it closes the bore 85 to prevent further reverse flow of operating fluid therethrough as the fluid operated pump unit 23 is being raised through the pump tubing 17. The fluid operated pump unit 23 passes upwardly through the pump tubing 17 until the tapered head member 77 on the perforated tubular strainer 81 passes between the sliding dogs 72 and 74 of the pump catcher 27 and engages the dash-pot element 78 therein. The dash-pot element 78 is free to move slowly vertically in the upper end of the tubular body member 65 of the pump catcher 27, but since the upper end of the tubular body member is closed, and since clearance between it and the dash-pot element is small, it acts as a dash-pot to reduce the jarring effect normally involved in stopping the upward movement of the fluid operated pump unit 23. As will be apparent, as soon as the tapered head member 77 passes above the sliding dogs 72 and 74, they will latch therebeneath by reason of the action of the coil springs 73 and 75 so as to retain the tapered head member 77, which in turn supports the fluid operated pump unit 23.

To remove the fluid operated pump unit 23 from the pump catcher 27, it is preferable to first rotate the tapered valve member 42 forty-five degrees in either direction so as to move the passages 43 and 44 out of registry with the other openings in the valve block 32 and thus shut off the supply of operating fluid to, and the discharge of fluid from, the well. The bleeder valve element 158 is then rotated so as to move the same off its seat 157 so as to open communication between the central chamber 35 and the well casing through the port 156, the valve bore 155, the bleeder port 170, and the bleeder pipe 171. This relieves the pressure in the pump tubing 17 above the fluid operated pump unit 23, and the tubular element 36 may then be unscrewed from the valve block 32 and the fluid operated pump unit 23 removed from the pump tubing 17.

If, for any reason, it is desired to remove the check valve means 129 from the well after the fluid operated pump unit 23 has been removed therefrom, a conventional spearing tool of any

standard construction well known in the art may be run into the well through the pump tubing 17 and into the lower check valve means through the conical opening 128. It will be appreciated that if the pump tubing 17 is filled with liquid, the weight thereof will maintain the metallic closure ball 137 tightly seated on its seating ring 138, and, consequently, it is important to provide a means whereby the closure ball can be readily moved from its seating ring so as to permit liquid thereabove to bleed back into the well before the lower check valve means 129 is raised through the pump tubing 17. This is provided by the release member 165. When a spearing tool is lowered through the conical opening 128, it will engage the upper end 167 of the release member 165, causing the same to rotate outwardly on the shoulders 164, which in turn causes the lower curved end 168 to rotate inwardly to move the closure ball 137 from its seating ring 138 and thus permit liquid above the closure ball to drain back into the well. This relieves the lower check valve means 129 of the weight of the column of fluid thereon in the pump tubing 17, and the spearing tool engages the annular shoulder 143 in the upper tubular element 132 of the check valve means to permit the check valve means to be raised through the pump tubing by the spearing tool which may be connected to a wire line for this purpose, as is well known in the art.

From the foregoing description, it will also be apparent that the lower check valve means 129 may be installed in the well in the position shown in Fig. 1 by inserting it into the upper end of the pump tubing 17, reconnecting the pump catcher 27 to the valve block 32, and then adjusting the four-way valve means 26 so as to convey operating fluid under pressure downwardly through the pump tubing so that it can pump the lower check valve means 129 downwardly therethrough. This is frequently desirable when a quick installation is desired. Similarly, the fluid operated pump unit 23 may then be inserted into the upper end of the pump tubing 17, and by suitable adjustment of the four-way valve means 26 the fluid operated pump unit may be pumped downwardly through the pump tubing to the operating position shown in Fig. 1. It will thus be apparent that I provide a construction by which a pump unit may be pumped into or out of a well in a minimum amount of time and a construction in which a check valve device may be independently pumped into seated position at the bottom of the well tubing. It will also be apparent that by providing the pump tubing 17 and the auxiliary tubing 24 with their axes laterally offset I am able to use an auxiliary tubing of relatively small diameter, thus materially reducing the cost of installation of my device.

Although I have shown and described a preferred embodiment of my device, it will be appreciated that other devices and elements may be substituted for the particular devices and elements shown herein without departing from the spirit of my invention, and I therefore do not intend to be limited to the specific construction shown but desire to be afforded the full scope of the following claims.

I claim as my invention:

1. In a well pumping device, the combination of: a first tubing set in a well; a second tubing set in the well beside said first tubing; means for connecting the lower ends of said tubings together in fluid communication; a pump of a size to be passed through said first tubing to the lower

end thereof; means for connecting the intake of said pump with the fluid in the well; and means for producing a flow of fluid downwardly through said second tubing and upwardly through said first tubing to move said pump upwardly through said first tubing to the ground level.

2. In a well pumping device, the combination of: a first tubing set in a well; a second tubing set in the well beside said first tubing; means for connecting the lower ends of said tubings together in fluid communication; a pump of a size to be passed through said first tubing to the lower end thereof; means for forming a seal between said pump and said first tubing; means for connecting the intake of said pump with the fluid in the well; and means for producing a flow of fluid downwardly through said second tubing and upwardly through said first tubing to move said pump upwardly through said first tubing to the ground level.

3. In a well pumping device, the combination of: a first tubing set in a well; a second tubing set in the well beside said first tubing; means for connecting the lower ends of said tubings together in fluid communication; a fluid operated pump of a size to be passed through said first tubing to the lower end thereof; means for connecting the intake of said pump with the fluid in the well; and means for producing a flow of fluid downwardly through said second tubing and upwardly through said first tubing to move said pump upwardly through said first tubing to the ground level.

4. In a well pumping device, the combination of: a first tubing set in a well; a second tubing set in the well beside said first tubing; means for connecting the lower ends of said tubings together in fluid communication; a pump of a size to be passed through said first tubing to the lower end thereof; means for connecting the intake of said pump with the fluid in the well; means for producing a flow of fluid downwardly through said second tubing and upwardly through said first tubing to move said pump upwardly through said first tubing to the ground level; and means at the upper end of said first tubing to receive and hold said pump after it has been raised by said flow of fluid.

5. In a well pumping device, the combination of: a first tubing set in a well; a second tubing set in the well beside said first tubing; means for connecting the lower ends of said tubings together in fluid communication; a pump of a size to be passed through said first tubing to the lower end thereof; means for connecting the intake of said pump with the fluid in the well; means for producing a flow of fluid downwardly through said second tubing and upwardly through said first tubing to move said pump upwardly through said first tubing to the ground level; and a detachable pump catcher at the upper end of said first tubing for receiving and holding said pump therein after said pump has been raised by said flow of fluid.

6. In a well pumping device, the combination of: a first tubing set in a well; a second tubing set in the well beside said first tubing; means for connecting the lower ends of said tubings together in fluid communication; a fluid operated pump of a size to be passed through said first tubing to the lower end thereof; means for connecting the intake of said pump with the fluid in the well; means for forcing fluid down through said first tubing to operate said pump; and means for reversing the flow of fluid so that it will flow

down through said second tubing and up through said first tubing to carry said pump to the upper end of said first tubing.

5 7. In a well pumping device, the combination of: a first tubing set in a well; a second tubing set in the well beside said first tubing, said second tubing being substantially smaller in diameter than said first tubing; means for connecting the lower ends of said tubings together in fluid communication; a pump of a size to be passed through said first tubing to the lower end thereof; means for connecting the intake of said pump with the fluid in the well; and means for producing a flow of fluid downwardly through said second tubing and upwardly through said first tubing to move said pump upwardly through said first tubing to the ground level.

10 8. In a well pumping device, the combination of: a tubing set in a well; a pump of a size to be passed through said tubing to an operating position adjacent the lower end thereof; pump catcher means at the upper end of said tubing adapted to receive and hold said pump when the same has been moved upwardly thereinto through said tubing, said pump catcher means including a housing adapted to receive said pump; means for moving said pump means upwardly through said tubing and into said housing; and dash-pot means associated with said pump catcher means for stopping the upward movement of said pump.

15 9. In a well pumping device, the combination of: a first tubing set in a well and having a pump seat at the lower end thereof; a pump adapted to seat on said pump seat, said pump having an inlet port communicating with the fluid in the well and a discharge port disposed therein so that when said pump is seated on said pump seat said discharge port will be a substantial distance above said pump seat; means for conveying pumped well fluid from said discharge port downwardly and around said pump seat so as to prevent the deposit of sand therearound; a second tubing set in said well; and means providing a fluid passage communicating between said first tubing adjacent said pump seat and the lower end of said second tubing.

20 10. In a well pumping device, the combination of: a tubing set in a well; a pump of a size to be passed through said tubing to an operating position adjacent the lower end thereof; pump catcher means at the upper end of said tubing adapted to receive and hold said pump when the same has been moved upwardly thereinto through said tubing, said pump catcher means including a housing adapted to receive said pump; means for moving said pump means upwardly through said tubing and into said housing; conduit means communicating between the interior of said housing and the well exterior to said tubing; and valve means in the line of said conduit means.

25 11. In a well pumping device, the combination of: a tubing set in a well; a pump of a size to be passed through said tubing to an operating position adjacent the lower end thereof; pump catcher means at the upper end of said tubing adapted to receive and hold said pump when the same has been moved upwardly thereinto through said tubing, said pump catcher means including a housing adapted to receive said pump; means for moving said pump means upwardly through said tubing and into said housing; conduit means communicating between the interior of said housing at the lower end thereof and the well exterior

to said tubing; and valve means in the line of said conduit means.

12. In a well pumping device, the combination of: a tubing set in a well; a pump of a size to be passed through said tubing to an operating position adjacent the lower end thereof; pump catcher means at the upper end of said tubing adapted to receive and hold said pump when the same has been moved upwardly thereinto through said tubing, said pump catcher means including a housing adapted to receive said pump; hydraulic means for moving said pump means upwardly through said tubing and into said housing; conduit means communicating between the interior of said housing at the lower end thereof and the well exterior to said tubing; and valve means in the line of said conduit means.

13. In a well pumping device, the combination of: a tubing set in a well; a pump of a size to be passed through said tubing to an operating position adjacent the lower end thereof; pump catcher means at the upper end of said tubing adapted to receive and hold said pump when the same has been moved upwardly thereinto through said tubing, including a housing adapted to receive said pump, a spring-urged dog element adapted to engage and support said pump, and resilient means in the upper end of said housing for cushioning the upper end-movement of said pump in said housing; and means for moving said pump upwardly through said tubing and into said housing.

14. In a well pumping device, the combination of: a tubing set in a well; a pump of a size to be passed through said tubing to an operating position adjacent the lower end thereof; pump catcher means at the upper end of said tubing adapted to receive and hold said pump when the same has been moved upwardly thereinto through said tubing, including a housing adapted to receive said pump, a fitting connected to said housing and having a spring-urged dog element therein projecting into the line of said pump; and means for moving said pump upwardly through said tubing and into said housing, said pump being adapted to engage and depress said dog element upon upward movement of said pump.

15. In a fluid operated pumping device, the combination of: a fluid operated pump for use in a well, said pump having an operating fluid inlet adapted to supply said pump with operating fluid under pressure to operate the same; and check valve means in said inlet adapted to permit a flow of operating fluid from said inlet to said pump but preventing a reverse flow thereof, said check valve means including a central passage communicating at one end with said inlet and at the other end with a valve chamber, a valve passage substantially aligned with said central passage and communicating between said valve chamber and said pump, a ball valve member adapted to seat in and close said valve passage in response to a flow of operating fluid to said

5 pump but operable to close said central passage in response to a reverse flow of said operating fluid, and a by-pass port of substantially smaller cross-sectional area than said valve passage and communicating between said chamber and said pump, operating fluid flowing through said by-pass port from said inlet to said pump when said ball valve member is seated in said valve passage.

16. In a well pumping device, the combination of: a first tubing set in a well; a second tubing set in the well beside said first tubing; a foot member secured to the lower ends of both of said tubings and having a longitudinal bore therethrough with an annular pump seat in said bore and a passage communicating between said bore above said pump seat and the lower end of said second tubing, the upper end of said longitudinal bore communicating with the lower end of said first tubing; and a pump of a size to be passed through said first tubing to the lower end thereof so as to seat on said pump seat, said pump having an inlet port communicating with said bore below said pump seat and a discharge port communicating with said passage.

25 17. In a well pumping device, the combination of: a first tubing set in a well; a second tubing set in the well beside said first tubing; a foot member secured to the lower ends of both of said tubings and having a longitudinal bore therethrough with an annular seat in said bore and a passage communicating between said bore above said seat and the lower end of said second tubing, the upper end of said longitudinal bore communicating with the lower end of said first tubing; a removable check valve element adapted to seat on said annular seat in said longitudinal bore and having a pump seat formed thereon; and a pump of a size to be passed through said first tubing to the lower end thereof so as to seat on said pump seat, said pump having an inlet port communicating with said bore below said pump seat and a discharge port communicating with said passage.

30 40 45 50 55 60 18. In a well pumping device, the combination of: a first tubing set in a well; a second tubing set in the well beside said first tubing; a foot member for connecting the lower ends of said tubings together in fluid communication; a pump of a size to be passed through said first tubing to the lower end thereof; means in said foot member for connecting the intake of said pump with the fluid in the well; an upper head member through which both of said tubings pass; a lower head member below the lower end of said foot member; a barrel surrounding said tubings and said foot member, the upper end of said barrel engaging said upper head member and the lower end of said barrel engaging said lower head member, said barrel having perforations therein adjacent the upper end thereof; and means for securing said lower head member to said foot member to retain said barrel.

CLARENCE J. COBERLY.
